UNITED STATES PATENT OFFICE.

LEWIS S. JOB, OF WARREN, OHIO, ADMINISTRATOR OF DANIEL JOB,
DECEASED.

ENGINE OR PUMP.

SPECIFICATION forming part of Letters Patent No. 595,631, dated December 14, 1897.

Application filed May 18, 1897. Serial No. 637,056. (No model.)

To all whom it may concern:

Be it known that DANIEL JOB, deceased, late of Warren, in the county of Trumbull and State of Ohio, having invented certain new and useful Improvements in Engines or Pumps, I, LEWIS S. JOB, administrator of the estate of the said DANIEL JOB, do hereby declare the following to be a full, clear, and exact description of the invention, such as will enable others skilled in the art to which it appertains to make and use the same.

This invention contemplates certain new and useful improvements in pumps or engines.

15 The primary object of the invention is to simplify the construction of the valve-casing and the arrangement of the valves and ports, so that a continuous outflow may be maintained. This is accomplished by providing 20 a cylinder into which open near each end ports leading from the valve-chamber, which forms the inlet, said valve-chamber being in communication at its end with a discharge-chamber. The ports of the valve-chamber 25 are alternately opened and closed. Through each of them the water or other fluid is made to travel in opposite directions, alternating at each end of the cylinder, whereby a continuous outflow is obtained. The improvements 30 are alike applicable to steam-valves. Ordinarily two corresponding casings are connected together and the piston or followers and valves are operated in unison, steam being admitted to one casing for effecting the 35 operation of the water-valves, or when steam is applied to the latter the other set of valves, &c., may be employed for producing an air-blast.

40 The invention will be hereinafter fully set forth, and particularly pointed out in the claims.

In the accompanying drawings, Figure 1 is a side view, the water-valve casing being in section. Fig. 2 is a plan view, both casings 45 being in section. Fig. 3 is a transverse sectional view on line 3 3, Fig. 1. Fig. 4 is a similar but enlarged view on line 4 4, Fig. 2.

Referring to the drawings, A designates the steam-casing, and B the water-casing. The 50 construction of both casings and the arrangement of the valves, &c., therein being sub-

stantially alike a description of one will suffice for both. Within the casing is a cylinder a, in which a piston or follower a' is capable of being moved back and forth. The 55 rod a² of this piston is common to both pistons and extends through stuffing-boxes a³ on the inner end plates a⁴. Within the casing, above the cylinder, are two cylindrical bores or chambers b b', an inlet-pipe b² opening 60 centrally into the former and an outlet-pipe b³ leading from the center to the latter. Communication between the ends of these bores or chambers b b' is had through ports b⁴, formed in the end plates of the casing. 65 The bore or chamber b communicates near its ends with the cylinder a by ports b⁵ b⁶, through which the water, steam, or other fluid is made to travel first downward and thence upward before passing into the bore or chamber b'. 70

C' designate two piston-valves mounted on a rod d and designed to slide back and forth in the bore or chamber b, alternately controlling the passages through the ports b⁵ b⁶. The rod d is extended from one casing 75 to the other, and both sets of piston-valves are secured thereon. As shown, however, the rod is disjointed and united by a coupling d', it sometimes being preferred to make the rod adjustable, in which event the valve-chamber of one casing is arranged on a line a little below the chamber of the other casing. To this valve-rod d are adjustably attached two tappets d² d³, which slide back and forth on a guide-bar d⁴, secured between the two 80 casings. To a stationary bracket d⁵, attached to base-plate d⁶, is fulcrumed the lower end of the lever E, which latter has two projections e e', which are designed to actuate the tappets d² d³, respectively. A tappet e², 85 clamped on the piston-rod, projects into a curved slot e³ in the lever E. The tappet has a forked guide e⁴, which slides back and forth on the valve-rod d, preventing the tappet from dropping. A weight e⁵ is adjustably 90 secured on lever E by a screw e⁶.

In practice steam is admitted to the casing A to effect the operation of the piston and valves therein, which in turn operate the corresponding parts of the casing B, into which 100 water is drawn through pipe b³. The description of the operation of the water-valves will

render clear that of the steam-valves. As the piston is moved from the right end of the cylinder toward the left end thereof the valves d d' will be moved to the right of the adjacent ports b^5 and b^6 , the movement of the piston serving to draw water from chamber b down through port b^5 into the cylinder. At the same time the water previously drawn into the cylinder on, say the left-hand side of the piston, will be caused to travel upward through port b^6 , and being arrested in one direction by valve d' will then pass through port b^4 into water-outlet chamber b' . As the piston starts on its return movement—that is, from left to right—the valve-rod d , having been previously moved so as to throw the valves d d' to the left of their respective ports b^5 b^6 , the water now in advance of said piston, previously drawn down through port b^5 , is caused to travel upward therethrough and pass through port b^4 to the water-outlet chamber. While this is occurring the first-described operation is being repeated at the left-hand end—that is, the water is being drawn down through port b^6 into the cylinder in rear of the piston or follower. Thus it will be seen that water is introduced into each end of the casing through a single port, through which it has to retravel in its passage to the outlet-pipe.

While certain means have been shown for operating the piston and the valves, it is obvious that various forms of mechanism may be employed for that purpose, it being necessary in all instances that the valves be operated in the manner described—that is to say, simultaneously with the piston or follower changing the direction of its travel; nor is it absolutely essential that the parts of one valve-casing be duplicated, although decidedly preferable.

In the construction shown, when the steam-piston approaches the end of its forward stroke the tappet e^2 strikes the end of the slot e^3 and throws over the lever E , causing one of the projections e e' to strike one of the tappets d^2 d^3 with sufficient force to reverse the valves. Steam and water are then admitted to the other end of their respective cylinders and the pistons are moved in reverse direction. The cushioning of the steam-piston is effected by the action of the lever reversing the valves just before the piston reaches the end of its stroke. The adjustability of the weight on the lever enables the tappets to be operated so as to work the valves with precision.

What is claimed is—

1. A pump or engine comprising a casing having parallel inlet and outlet chambers, a cylinder, and two sets of ports, one set connecting said inlet-chamber with said cylinder, and the other set connecting said inlet and outlet chambers, a piston in said cylinder, and valves in said inlet-chamber, for opening and closing said sets of ports, substantially as set forth.

2. A pump or engine comprising a casing having upper inlet and outlet chambers arranged parallel with each other, and having, respectively, centrally-disposed inlet and outlet openings, a lower cylinder, ports leading from said inlet-chamber to said cylinder and from said inlet-chamber to said outlet-chamber, a piston movable in said cylinder, and valves in said inlet-chamber for alternately opening and closing said ports, substantially as set forth.

3. The combination with the two casings, each having upper, parallel inlet and outlet chambers, a lower cylinder parallel with said chambers, and ports leading from said inlet-chamber to said cylinder, and from said inlet-chamber to said outlet-chamber, of the pistons in said cylinder on a common rod, a tappet on said piston-rod, valves in said inlet-chambers, a rod or rods therefor designed to move said valves in unison, tappets on said latter rod or rods, and a lever designed to be engaged by said tappet of said piston-rod and caused to strike said tappets of said valve rod or rods, substantially as set forth.

4. The combination with the two casings, each having upper, parallel inlet and outlet chambers, a lower cylinder parallel with said chambers, and ports leading from said inlet-chamber to said cylinder, and from said inlet-chamber to said outlet-chamber, the pistons in said cylinder, a rod common to said pistons, and the valves provided with rods connected together, of the tappets secured on said rods, a guide therefor, a lever pivoted between said tappets and provided with a slot, a tappet on said piston-rod engaging with said slot, and a weight adjustably secured upon the upper part of said lever, substantially as set forth.

In testimony whereof I have signed this specification in the presence of two subscribing witnesses.

LEWIS S. JOB,
Administrator of the estate of Daniel Job.
